United States Patent Office

Des. 206,826
Patented Jan. 31, 1967

206,826

ORGAN CONSOLE

Don Marshall Stone, 4 Potomac Court,
Alexandria, Va. 22314

Filed June 15, 1966, Ser. No. 2,685

Term of patent 14 years

(Cl. D56—2)

FIG. 1

FIG.2

FIGURE 1 is a front perspective view of an organ console embodying the new design of the present invention; and

FIGURE 2 is a rear perspective view of the organ console of FIGURE 1.

The dominant features of the design according to the invention reside in the portions shown in solid lines.

I claim:

The ornamental design for an organ console, substantially as shown and described.
